UNITED STATES PATENT OFFICE.

MOSES H. DRENNAN, OF ST. LOUIS, MISSOURI.

HOLDER FOR NURSING-BOTTLES.

1,117,008.

Specification of Letters Patent. Patented Nov. 10, 1914.

Application filed August 22, 1913. Serial No. 786,060.

To all whom it may concern:

Be it known that I, MOSES H. DRENNAN, a citizen of the United States, residing in the city of St. Louis and State of Missouri, have invented new and useful Improvements in Holders for Nursing-Bottles, of which the following is a specification.

This invention relates to holders for nursing bottles, and has for its principal objects to produce a simple and efficient device for supporting a nursing bottle within easy reach of an infant; to provide for a compensating movement of the holder with the bottle thereon so as to insure the proper positioning of the bottle at an inclination in order that the nipple will be at all times filled with milk; to provide a collapsible structure which may be readily folded and carried in a pocket or a handbag; and to attain certain advantages which will herein-after more fully appear.

In the accompanying drawing—Figure 1 is a perspective view of a collapsible nursing bottle holder, illustrating an adaptation 25 of the invention, the bottle being shown by dotted lines; Fig. 2 is a side elevation of the holder with the bottle thereon; and Fig. 3 is a miniature perspective view illustrating the holder in a collapsed and folded condition.

Generally stated, the device comprises a pair of oppositely-disposed hinged jaws adapted to grip the side of the bottle, a releasable support for the neck of the bottle, 35 and a pair of supporting legs arranged to span the body of the infant and to permit the support to be rocked so that the bottle may be tilted to different angular positions.

As shown in the drawing, the device is 40 made of wire which is bent into form. A substantially rectangular frame portion or base 1 is provided with loops or eyes 2, 3, on opposite sides and near its ends. In these eyes, jaws or wings 4 are hinged. 45 These jaws are curved to correspond substantially to the contour of the bottle, and, as shown, comprise re-bent portions of wires 5, which constitute the supporting legs. The bends or crimps 6 at the intersection of 50 the supporting legs 5 and jaws 4 are engaged in the eyes 2. The free end portions 7 of the jaws 4 are hooked so as to be releasably engaged in the eyes 3. The jaws, adjacent to the said hook portions 7, are 55 provided with reentrant portions 8 which serve to prevent the hooked end portions of

the jaws from sliding through said eyes 3 too far.

A bail, comprising a straight intermediate portion 9, is hinged through loops 10 provided on the frame 1 intermediate the loops 2 and 3. The arms 11 of this bail are curved like said jaws 4 so as to conform to the contour of the bottle, and are adapted to retain the jaws in contact with the bottle. 65

Extending forwardly from the frame portion 1 is a support 12 for the neck of the bottle. Preferably, this support is made integral with the frame portion 1 by looping or rebending and twisting a single piece of 70 wire. From the twisted neck portion 13 the side members of the support 12 are spread apart so as to provide a space 14 through which the beaded mouth portion of the bottle may be inserted, easily between said 75 two side members. At the outer end of the support the side members 12 are brought closer together, and the portion of the wire connecting the ends of said side members is looped and struck upward, as at 15, so as 80 to span the neck portion of the bottle, the gap at the bottom of the loop being less than the diameter of the neck so that the neck may be snapped into the loop 15, the resiliency of the wire being sufficient to support the neck portion of the bottle. 85

In using the device, the bail 9 is moved so as to disengage the hinged jaws 4 in order that the latter may be swung apart to receive the body of the bottle. The neck portion of the bottle is inserted downwardly between the supporting members 12 and then the neck is snapped up into the loop 15. The body of the bottle is then dropped down upon the frame portion 1, and the jaws 4 are brought up against the opposite sides 90 of the bottle. The bail 9 is then swung so that its arms 11 clamp said jaws in place. In practice the arms 11 of the bail are made so that they have to be sprung slightly in 100 moving them into locking position. The bottle being placed on the support, the support is then placed over the body of the infant, the legs 5 being arched with relatively wide spread and high clearances so as 105 to support the bottle free above the body of the infant. The holder portion is arranged so that when the legs are vertical the bottle is at a slight inclination, and, obviously, the device may be rocked on the feet 5^a which are provided by looping the ends of the wire, 110 as shown. By thus looping the wire the

ends of the legs 5 are made blunt so as not to injure the infant. It is also preferable to loop the ends of the arms 11 of the bail, as at 11^a.

5 When the device is not in use it may be readily collapsed and folded so as to be carried conveniently in the pocket or handbag. To collapse the device it is only necessary to unhook the portions 7 from the 10 eyes 3, and swing the leg portions 5 so that they will be crossed over the neck-supporting members 12, as shown in the diagram in Fig. 3.

Obviously the device admits of considerable modification without departing from the invention. Therefore, I do not wish to be limited to the exact construction and arrangement shown.

I claim:

20 1. A tiltable holder for nursing bottles comprising a body portion having means for releasably engaging and holding a bottle thereon, and means for supporting said body portion at an elevation, said last named 25 means comprising a pair of leg members, respectively, extending outwardly and downwardly from opposite sides of said body portion and transversely with respect to the bottle.

30 2. A holder for nursing bottles comprising a body portion having jaws hinged on opposite sides thereof and adapted to releasably engage the sides of the bottle, releasable means for retaining said jaws in 35 contact with the bottle, a forwardly-extending support adapted to releasably engage the neck portion of the bottle, and a pair of supporting legs extending transversely with respect to the bottle and adapted to support 40 the holder, whereby the holder may be tilted.

3. A holder for nursing bottles comprising a body portion, said body portion comprising a rectangular frame having a forwardly-extending support for the neck of

the bottle, said frame and support being 45 made of a single piece of wire, said support comprising a spaced pair of side members connected at their outer ends by an upstanding loop, said rectangular frame portion having eyes formed in its side members near 50 its ends and at the middle thereof, hinged jaws adapted to releasably engage the sides of the bottle, said jaws comprising wire loops curved to conform to the contour of the bottle, one arm of each of said jaws being 55 extended to constitute a supporting leg, the portion of the wire at the junction of the arm and supporting leg being hinged in the eye near one end of said frame, the other arm having its free end portion hooked so 60 as to engage the eye at the opposite end of said rectangular frame, and a bail having a straight intermediate portion extending transversely across said frame through the middle eyes thereof, the end portions of said 65 bail being curved to correspond to the contour of the bottle and adapted to engage said jaws so as to releasably hold them in contact with the bottle.

4. A holder for nursing bottles comprising 70 a body portion having means for releasably engaging and holding a bottle thereon, and a pair of supporting legs respectively extending outwardly and downwardly from opposite sides of said body portion, said 75 legs being disposed transversely with respect to the bottle and with relatively wide spread and high clearance, whereby the holder is adapted to span clear of the body of an infant and is tiltable thereover at will. 80

In testimony whereof, I have hereunto set my hand in presence of two subscribing witnesses.

MOSES H. DRENNAN.
